APPARATUS FOR RECOVERY OF BLACK OR
OTHER MAGNETIC SANDS OR SILTS FROM
STREAMS

Joseph E. Parker, Houston, Tex.

Refiled for abandoned application Serial No.
678,712, July 1, 1933. This application Sep-
tember 24, 1936, Serial No. 102,429

11 Claims. (Cl. 209—215)

The invention relates to an apparatus for recovering black or other magnetic sands or silt from streams and the present application is filed to take the place of an abandoned application 5 Serial No. 678,712, filed July 1, 1933, by me for the same subject matter as that of the present application.

The object of the present invention is to provide a simple, practical and efficient apparatus 10 of strong, durable and comparatively inexpensive construction, designed to be arranged upon the bed of a stream and to extend from the bottom of the stream either to the surface of the water or any distance above or below the surface so 15 as to lie in the path of sand or silt traveling in traction, that is, sliding on the bottom of the stream and also sand or silt flowing in suspension and adapted to intercept and attract and collect such magnetic sands and silt, and capable 20 of being readily hoisted from the bed of a stream and moved to a position over a container and of discharging the collected sand or silt and depositing the same within a suitable container.

A further object of the invention is to provide 25 an apparatus of this character equipped with electro-magnets adapted to be energized by a generator either on the bank of a stream or on a barge or the like, and capable of enabling the electro-magnet to be readily energized and de- 30 energized for attracting and collecting the magnetic values in the stream, and of quickly depositing such values when the apparatus has been moved over a container or receptacle for the magnetic sand or silt.

It is also an object of the invention to equip 35 the apparatus with a grizzly adapted to form a combined guard and deflector in addition to permitting the sand and silt to pass through it to the magnets so that the sand and silt will be 40 operated on by the apparatus and rocks and floating debris, such as logs, will be deflected and caused to pass to either side of the apparatus and thereby prevented from passing through and lodging in the apparatus.

With the above and other objects in view, the 45 invention consists in the construction and novel combination and arrangement of parts herein- after fully described, illustrated in the accom- 50 panying drawings and pointed out in the claims hereto appended, it being understood that various changes in the form, proportion and minor de- 55 tails of construction, within the scope of the claims, may be resorted to without departing from the spirit or sacrificing any of the advan-

In the drawings:—

Fig. 1 is a perspective view of an apparatus constructed in accordance with this invention, for the recovery of black or other magnetic sands or silts from streams. 5

Fig. 2 is a transverse sectional view of the same.

Fig. 3 is a detail view of a portion of one of the magnet supporting members, illustrating the arrangement of one of the front magnets.

Fig. 4 is a similar view illustrating the arrangement of one of the intermediate magnets. 10

Fig. 5 is a view of the wiring diagram.

In the accompanying drawings in which is illustrated the preferred embodiment of the invention, the apparatus for the recovery of black 15 or other magnetic sand or silt from streams comprises in its construction a plurality of spaced horizontal magnet supporting members 1, preferably arranged in a rectangular group and composed of spaced vertical tiers and formed by horizontal sets which are detachably and removably supported by transverse rods 2. The magnet supporting members which may be of any desired number, preferably consist of wooden poles or tubes which preferably extend longitudinally of 20 the apparatus, and the transverse rods which are horizontally disposed, pass through the end portions of the magnet supporting members and through vertical standards 3 arranged in pairs at the front and rear of the apparatus and located 25 at opposite sides thereof, as clearly shown in Fig. 1 of the drawings. Any number of the standards and sets of transverse rods may, of course, be employed, and the transverse rods are detachably secured to the standards by any suitable means to enable them to be removed for de- 30 taching any of the magnet supporting members for the repair of electro-magnets 4 and 5, or other purpose. 35

The standards 3 which are vertical, are preferably provided at their upper ends with suitable eyes 6 which receive transverse rods 7 and spacing tubes 8 which space the lower ends of chains 9 of a hoisting apparatus. 40

The hoisting apparatus which may be of any 45 desired construction and which in practice will be operated by a suitable power includes a beam or boom 10, a cable 11 and the said chains 9 which are connected at their upper ends to the lower end of the cable and extend downwardly 50 and outwardly in a diagonal direction and at an inclination to the upper ends of the standards 3. The rods 7 pass through suitable end links of the chains and the spacing tubes or sleeves 8 main- 55 tain the ends of the chains in proper position at

the sides of the apparatus at the front and back thereof. The apparatus is designed to be arranged at and rest upon the bottom or bed of the stream and the hoisting mechanism will enable the apparatus to be readily deposited in the stream upon the bed thereof, and will also enable the same to be easily and quickly removed therefrom for discharging and depositing in a suitable container an accumulation of magnetic sand or silt collected and recovered by the apparatus.

The electro-magnets may be of any desired form or construction, either horseshoe magnets or straight bar or core magnets. The electro-magnets 4 are mounted upon the front ends of the supporting members 1 which are bored at intervals between their ends to provide openings 12 for the reception of the intermediate magnets.

5. The openings 12 are arranged both vertically and horizontally to dispose the magnets alternately in a horizontal and vertical position, but they may be arranged in any other position and may, if desired, extend from two opposite faces of the supporting member or from only one side 25 or face thereof.

The electro-magnets are designed to be supplied with current from a generator 13 which may be operated by a gasoline engine, or any other suitable power, and which may be located either on the bank of a stream or on a barge, float or the like. A suitable switch 14 is provided for enabling the current to be turned on or cut off for energizing and de-energizing the magnets to enable the apparatus to collect a load of the 30 magnetic material moving along the bottom of the stream or floating in suspension in the stream and to quickly release and discharge the accumulated material when the apparatus is lifted from the stream and moved over a suitable container.

40. The apparatus is provided at its front with an approximately V-shaped grizzly 15 forming a combined guard and deflector and composed of two sides arranged at an angle and connected together at the front ends and at their rear ends 45 with the adjacent standards 3 or other portion of the apparatus. The grizzly which is preferably constructed of steel, is provided at each side with a grating which may be formed by spaced parallel strips 16 extending over an opening 17, as clearly illustrated in Fig. 1 of the drawings, but the grating may be of any desired construction, and the slits or openings in the grating are preferably horizontal, as shown and are of sufficient size to permit sand and silt to readily pass 50 through the grizzly so as to be operated on by the magnets of the apparatus and the said openings or slits in the grizzly are sufficiently narrow to prevent any rock or floating debris from passing through the grizzly and lodging in the machine.

60. The grizzly or any of the parts thereof may be magnetized and be in the form of either permanent or electro-magnets. The apparatus may be made of any desired size and may extend either from the bottom of the stream to the surface thereof, or to a point above the surface, or it may terminate at a point below the surface. It may be left unattended at intervals for continuous operation and after it has accumulated a sufficient quantity of magnetic sand or silt, it may be readily lifted from the bottom of a stream 65 and moved to a position above a container for the reception of the recovered values. The accumulated magnetic sand and silt may be quickly and thoroughly discharged from the apparatus and deposited in the receptacle by simply oper-

ating a switch and cutting off the current to the magnets and thereby de-energizing the same. After a load or accumulation has been deposited in the container the switch is operated to re-energize the magnets and the apparatus is returned to the bottom of the stream for repeating the operation. The magnet supporting members, the means for securing and connecting the same and the grizzly constitutes the frame of the apparatus and the weight of the apparatus is ample for maintaining it in proper position on the bed of the stream. The wiring of the electro-magnets and the feed wires for supplying the electro-magnets with current may be insulated in any desired manner and may be of any preferred arrangement, the chains 9, the cable 11 and the boom or beam 10 forming ample supports for the feed wires.

What is claimed is:—

1. An apparatus of the class described including a frame adapted to be arranged upon the bed of a stream in the path of sand and silt traveling down the stream, said frame including a plurality of longitudinally disposed magnet supporting members consisting of poles and arranged in vertical tiers, the members of each tier being spaced apart and the tiers being spaced from one another, end electro-magnets mounted on the supporting members at the front ends thereof, intermediate electro-magnets carried by the supporting members and arranged at intervals along the same in openings thereof, and hoisting mechanism connected with the frame for handling the same.

2. An apparatus of the class described including a frame adapted to be arranged upon the bed of a stream in the path of sand and silt traveling down the stream, said frame comprising a plurality of longitudinally disposed magnet supporting members spaced vertically and horizontally and forming an approximately rectangular group, standards located at opposite sides of the group, transverse rods connecting the standards and passing through the magnet supporting members, electro-magnets carried by the supporting members, and hoisting mechanism connected with the said standards for handling the frame.

3. An apparatus of the class described including a frame adapted to be arranged upon the bed of a stream in the path of sand and silt traveling down the stream, said frame comprising a plurality of longitudinally disposed magnet supporting members spaced vertically and horizontally and forming an approximately rectangular group, vertical standards located at opposite sides of the group of supporting members, means for connecting the supporting members with the standards, transverse rods connecting the upper ends of the standards, hoisting mechanism having flexible connections connected with the upper ends of the standards, and electro-magnets carried by the supporting members and arranged at intervals on the same.

4. An apparatus of the class described including a frame adapted to be located in a stream in the path of sand and silt traveling down the stream, said frame including a plurality of longitudinally disposed magnet supporting members arranged in vertical tiers, the members of each tier being spaced apart and the tiers being spaced from one another, and means extending transversely of the frame for the support of said magnet supporting members, and electro-magnets.

mounted on the supporting members at intervals along the same.

5. An apparatus of the class described including a frame adapted to be arranged in a stream in the path of sand and silt traveling down the stream, said frame including a plurality of longitudinally disposed magnet supporting members arranged in vertical tiers, the members of each tier being spaced apart and the tiers being spaced 10 from one another, means extending transversely of the frame and transversely through said magnet supporting members to support the magnet supporting members, and electro-magnets carried by the supporting members and arranged at 15 intervals along the same.

6. An apparatus of the class described including a frame adapted to be arranged in a stream in the path of sand and silt traveling down the stream, said frame including a plurality of longitudinally disposed magnet supporting members arranged in vertical tiers, the members of each tier being spaced apart and the tiers being spaced 20 from one another, means extending transversely of the frame and transversely through said magnet supporting members to support the magnet supporting members, said magnet supporting members having openings therein, and electro-magnets disposed in said openings.

7. An apparatus of the class described including a frame adapted to be arranged in a stream in the path of the sand and silt traveling down the stream, said frame including a plurality of longitudinally disposed magnet supporting members, arranged in vertical tiers, the members of 35 each tier being spaced apart and the tiers being spaced from one another, transversely disposed rods having engagement with the longitudinally disposed magnet supporting members to support the same, the magnet supporting members having transverse openings therein arranged alternately at different angles with relation to one another, and electro-magnets mounted in said transverse openings of the supporting members.

8. An apparatus of the class described including a frame adapted to be arranged in a stream in the path of the sand and silt traveling down the stream, said frame including a plurality of longitudinally disposed magnet supporting members, arranged in vertical tiers, the members of each tier being spaced apart and the tiers being 40 spaced from one another, transversely disposed rods having engagement with the longitudinally disposed magnet supporting members to support the same, the magnet supporting members having transverse openings therein arranged alternately 45 at different angles with relation to one another,

and electro-magnets mounted in said transverse openings of the supporting members, the upstream end of each of the magnet supporting members having an opening therein and an electro-magnet disposed in each of the last mentioned openings. 5

9. An apparatus of the class described, including a frame adapted to be arranged in a stream in the path of sand and silt traveling down the stream, said frame comprising a plurality of longitudinally disposed magnet supporting members spaced vertically and horizontally and forming an approximately rectangular group, vertical standards located at opposite sides of the group of supporting members, means for connecting 10 the supporting members with the standards, transverse rods disposed in angular relation with the supporting members and connecting opposite standards, and electro-magnets carried by the supporting members. 15

10. An apparatus of the class described including a frame adapted to be arranged in a stream in the path of sand and silt traveling down the stream, said frame comprising a plurality of longitudinally disposed magnet supporting members 20 spaced vertically and horizontally and forming an approximately rectangular group, vertical standards located at opposite sides of the group of supporting members, means for connecting the supporting members with the standards, 25 transverse rods connecting the standards, electro-magnets carried by the supporting members, and a grizzly of approximately V-shape having angularly related sides adapted to deflect debris and prevent the same from lodging in the device, 30 said sides of the grizzly having a grating with apertures for the passage of sand and silt. 35

11. An apparatus of the class described including a frame adapted to be arranged in a stream in the path of sand and silt traveling down the 40 stream, said frame comprising a plurality of longitudinally disposed magnet supporting members spaced vertically and horizontally and forming an approximately rectangular group, rods extending transversely across the frame and having 45 engagement with said magnet supporting members to support the latter effectively in the frame, electro-magnets carried by the supporting members and arranged at intervals along the same, and an apertured grizzly connected to the frame 50 at the upstream end of the latter to prevent debris from gaining access to the interior of the frame and yet permit of the passage of sand and silt to the interior of the frame. 55
